CONCENTRIC SHELL HOT-AIR HEATER

Sidney J. Heiman, St. Louis, Mo.

Application April 11, 1945, Serial No. 587,680

1 Claim. (Cl. 126—106)

1

This invention relates generally to heaters, but more particularly to those heaters which are adapted to be installed within the room or space to be heated, and wherein the combustion chamber will have a flow of air in contact therewith to thereby become heated and thence be discharged from the device to heat the desired space.

One of the objects of my invention is to so construct a device of the kind described, that air will be directed and guided in a predetermined path from intake to discharge, absorbing a maximum of heat from its contact with the heated parts of the combustion chamber, with high efficiency.

Another object of my invention is to so construct a device of the kind aforesaid, that said air will be guided in a plurality of consecutively reversed directions while contacting the initially heated surfaces of the structure during such travel, and thence be discharged as the room-heating medium.

An added object of this invention is to construct a heater of the kind described, wherein the combustion chamber will consist of a double-walled shell, with the inner wall being reentrant and depending from the top of the chamber to a point above the bottom of the outer wall, said inner wall having its bottom sealed, and said shells closed across their upper ends, together with means to direct the flow of air in successively reversed directions to engage substantially the full surface exteriorly of the combustion chamber.

Further objects of this invention are to so construct a heater of the kind described, that there will be a maximum of radiation surface in contact with the air circulated therethrough, and within a very small cubic amount of heater body, and wherein the hottest part of the flame in the combustion chamber will be substantially at the sealed bottom of the reentrant inner shell of the combustion chamber.

A still further object of this invention is to so construct a heater of the kind aforesaid, that the greatest advantage is had from the radiation space of the same, by transferring said heat directly from the points where it exists in the radiation surface of the heater, by passing a current of air over the same to thereby become heated, prior to discharging said air into the room to be heated.

An additional object of my invention is to provide a heater construction wherein there will be little tendency of overheating or burning out of the walls of the combustion chamber, inasmuch

2

as the heat is extracted therefrom rapidly, evenly and continuously, by a current of air passed in contact with the heated surfaces of the heater.

5 Other objects of this invention are to so construct a heater of the kind described, that will be simple and easy to make and use, not likely to get out of order, will keep clean over long periods of time, will eliminate indirect heating surfaces in favor of direct or radiant heating surfaces, wherein there will be a fairly direct flow of combustion gases from their generation to their discharge, will operate with comparatively low drafts and thereby enhance the safety of operation inasmuch as the said gases travel substantially continuously upwardly to and through the flue.

10 Many other objects and advantages of the construction herein shown and described will be obvious to those skilled in the art to which this invention appertains, as will be apparent from the disclosures herein given.

15 To this end, my invention consists in the novel arrangement, construction and combination of parts and the uses mentioned, as will be more clearly pointed out in the following specifications.

20 In the drawings, wherein like reference characters represent like or corresponding parts throughout the views,

25 Figure 1 is a substantially horizontal cross-sectional view taken through the structure; and

30 Figure 2 is substantially a vertical cross-sectional view taken through the same.

35 Referring more particularly to the drawings, wherein I have illustrated a preferred embodiment of my invention with as few parts as possible, in order to show the invention more clearly, there is shown a space heater generally, with its combustion chamber 1 formed between 40 a pair of radially spaced inner and outer shells or walls 2 and 3, respectively, said inner wall being reentrant or depending into the outer shell, somewhat as shown.

45 A top wall 4 is provided across the space between the tops of the pair of cooperating shells 2 and 3 to form the top end closure thereat, and the bottom end of the inner shell 2 is provided with a transverse wall 5 to seal thereacross.

50 Any suitable source of heat, as for instance the pot of an oil burner 6, may be interposed within the combustion chamber, below the sealed bottom of the inner shell of the said chamber, and a flue 7 may be provided to lead outwardly from the upper end of said chamber in the usual manner. In order to slow down the flow of com-

bustion gases upwardly of the chamber, a transverse baffle 8 may be positioned between said pair of shells forming said chamber, preferably adjacent the upper end of the chamber, this baffle sealing off passage of said gases of combustion, except at a point preferably remote from said flue. Although said gases move constantly up to the flue, they move somewhat slower than without such a baffle, and this flow of gases makes for safety in operation with a low draft.

An innermost shell or wall 9 extends vertically from its open lower end 10 to a point spaced above the top wall 4 of the combustion chamber and is spaced radially from the adjacent surface of the shell member 2 to provide an air passage-way between said shells in a manner about to be described.

An outermost shell or tube 11 encloses the outer periphery of the shell member 3 to provide an air passage between the two, and a top closure 12 bridges across the tops of the members 9 and 11 to seal the same against other than the predetermined path of travel of air as indicated by the arrows, said top wall element 12 being spaced above the top wall 4 of the combustion chamber.

Openings 13 may be provided through the lower end of the outermost shell wall 11, for discharge of heated air therethrough into the room or other space to be heated, and in that case, an air intake chamber 14 is formed above the top wall 12, by placement of a wall 15 spaced above the wall 12 to form said intake chamber together with said last-mentioned wall 12, the inlet ports being indicated at 16.

With the intended manner of air movement just set forth, it is necessary to place a fan or blower 17 to propel said air as indicated by the arrows in the drawings, and for that purpose said fan may be positioned at some point in the chamber 14 adjacent the upper end of the shell 9, so that said chamber 14 serves substantially as a plenum chamber.

Assuming that the air intake is at 16 and the discharge at 13, and the heater is in operation, the enclosing walls of the combustion chamber will become heated, with the greatest degree of heat being adjacent the bottom wall 5, and the gases of combustion will travel upwardly continuously and past the baffle and outwardly through the flue, the air entrained in the plenum chamber will be propelled downwardly through the innermost shell wall 9 to strike the said wall 5, and reverse its vertical direction and travel upwardly between the opposed surfaces of the shells 2 and 9 to the top of said combustion chamber, where it travels radially outwardly and then in a vertical direction reversed from its last reversal, downwardly in the space between the shell walls 3 and 11, at the lower end of said space being discharged outwardly into the room or space to be heated, through the outlets 13.

Thus it is seen that there is a very long path of travel of air in contact with the radiation surfaces of the heater, said air being out of communication with the gases of combustion however, and that substantially all of the wall surface of the combustion chamber is thus wiped by said entrained air, to obtain a direct transferance of heat to the latter and get the greatest advantage of such radiation surface.

Indirect heating surfaces are thus avoided, in favor of the direct or radiating heating surfaces of the combustion chamber. There is a moving body of air in circulation with all of the wall surface of the combustion chamber.

Of course it is to be understood that the natural flow of air through the path just described, may be employed, where it is desired to discharge the heated air through the ports 16 and use the openings 13 as inlets, and in which case the fan may either be dispensed with or its air-propelling direction reversed, the air still traveling in a series of consecutively reversed directions and in close contact with the combustion chamber wall surfaces during such movement.

Although the combustion chamber is hottest adjacent the bottom of the reentrant shell, there is little or no danger of the same burning out thereat, inasmuch as substantially the coldest air contacts with said hottest region to immediately absorb the radiated heat of the latter.

In order to get an even more efficient transfer of heat from the combustion chamber wall, a sheet of good heat-conducting material, as of metal for example, may be interposed to extend vertically in the space between the walls 2 and 9, and preferably made sinuous or corrugated as at 18, said sheet being either integral with said wall 2 or welded or otherwise well bonded thereto so as to act as an extension of said radiating surface, this element 18 preferably terminating somewhat above the open bottom of the wall 9, so that there is no undue interference with the upward reversal of the air after it has made its downward movement through the last-mentioned shell 9. The element 18 thus multiplies the effective radiation surface of the wall 2 and more efficiently transfers its heat to the air passing along either side of the corrugations.

A covering or insulating wall 19 may be used to enclose the entire structure, and in order to avoid building up of undesirably high wall temperatures, vents 20 may be provided leading from the exterior into the space between said covering and the shell 11.

It may be stressed here, that the inner or reentrant shell wall of the combustion chamber terminates at the sealed bottom 5 at the height of the hottest zone of the flame from the pot or burner 6, or other source of combustion. Hence, there is an almost immediate transference of heat from the zone of maximum temperature within the combustion chamber, to the shell elements 6 and 2, and from the latter portions of the shell insert to the air circulated as hereinbefore shown and described, thereby resulting in maximum efficiency of heat transference from said hottest part of the furnace.

A heater constructed as herein described will be exceptionally safe in its operation, inasmuch as it will work efficiently under fairly low drafts, and the flow of the combustion gases will be progressively and constantly upwardly to the level of the flue.

Having thus described my invention, it is obvious that various immaterial modifications may be made in the same without departing from the spirit of my invention; hence I do not wish to be understood as limiting myself to the exact form, arrangement, construction and combination of parts herein shown and described, except as limited by the state of the art to which this invention appertains, and the claim hereunto appended.

70 What I claim as new and desire to secure by Letters Patent is:

In a heater construction for discharging heated air into a room at substantially floor level, concentrically spaced upright inner and outer walls, 75 a closure across the tops of said walls, and a

closure across the bottom of said inner upright wall to thereby provide a combustion chamber enclosed by said upright walls and top and bottom closures, a pair of shells concentrically positioned relative to said upright walls, one of said shells being exteriorly of and spaced from said outer upright wall and the other shell being interiorly of the inner upright wall, said last-mentioned shell having an open lower end terminating above said bottom closure, said outer shell having a cold air inlet thereinto, and the space within said outer upright wall having a hot air outlet therefrom, means for entraining air from said one shell downwardly into said inner shell so that the same will travel in reversed directions in sequence along the inner and outer side of the innermost shell and in a direction then reversed from the last-mentioned of said reversed directions along the outer wall of said outer upright wall, and an upright heat-conducting corrugated element arranged between said innermost shell and the adjacent wall surface of the inner of the upright walls and carried by the latter and entirely spaced from the innermost shell and having passages through which said air is guided there- 25

past, said corrugated element engaging only said adjacent wall entirely above the bottom of the innermost shell to conduct heat directly to the air flowing in contact therewith.
